UNITED STATES PATENT OFFICE.

CHARLES H. HAUPT, OF ELIZABETH, NEW JERSEY.

GOLF CLUB.

Application filed March 21, 1928. Serial No. 263,239.

This invention relates to golf clubs of the wooden head or driver type, including drivers, brassies and spoons and will be fully understood from the following description 5 taken in conjunction with the appended drawing.

In the drawing Fig. 1 is a plan view of a driver constructed in accordance with the invention, and Fig. 2 is a diagram showing 10 the means for generating the curve of the striking face.

Referring to Fig. 1, numeral 1 designates the shaft of the club, which may be of usual construction, and numeral 2 designates the 15 head. This may likewise be of any ordinary form, save for the shape of the striking face to which the present invention is directed. This face, designated 3, is lofted, that is, inclined rearwardly and upwardly from the 20 sole of the club head in the usual manner to an extent dependent upon the intended use of the club, that is, only slightly for drivers, somewhat more in general for brassies, and most for spoons. Each element (as 25 fixed by the intersection of a horizontal plane parallel with sole of the club and the face) is as to its inner portion nearest the shaft attachment point, straight, and as to its outer portion, away from the shaft, by 30 increasing angularity or curvature, so that the face as a whole is plane or approximately plane in its near side and noticeably concave as to its outer side. The general configuration thus produced is shown in Fig. 1. 35 The arrow 4 in that figure represents the point on the face which is normally used to address the ball. This point should be at the approximate center, or if displaced, then slightly nearer the shaft than the far end 40 of the face.

To determine the exact curvature of the elements of the face 3, resort is had to graphic plotting as shown in Fig. 2. Here the axis of the shaft is represented (in fore-shortened plan view) by a straight line 45 designated 1', and an element of the striking face by 3'. (It is to be understood that the sole of the club head is in the plane of the paper.) The point of normal address 50 to the ball is designated by the arrow 4'. At this point of normal address, and from thence inward toward the handle of the shaft, the element of the striking face is straight, and may either be parallel with 55 the shaft as in common practice or inclined somewhat backward as is occasionally the

case with existing clubs of the prior art. To determine the points which fix the curvature of the outer section of the element the procedure is as follows: A line *a* is drawn 60 through the end of the shaft 1' at right angles thereto and a point *b* is chosen on such line. The point *b* lies away from the shaft 1' in the direction of the intended flight of the ball. From point 1 a straight 65 line 1'' is drawn to point C, which represents the intersection of the arrow 4' and shaft 1' (extended). This line 1'' represents the hypothetical position of the club shaft 1, as seen in plan view when the hands 70 of the player are brought through in the correct swing but with the shaft of the club sloping backwardly to the maximum extent it is deemed possible to provide for. This fault in technique I have found to be one 75 of the commonest causes of slicing. Treating the line 1'' as the axis of the club shaft, the relative position of the club face is located with reference thereto by measuring off the length of the line 1' to point C, and 80 taking an equal distance on line 1'' from point *b*. From the point so fixed a perpendicular 3^a is erected, on which is measured off the distance from point C to the straight 85 inward portion of the club face. This gives the point 3^b corresponding to the center point of the face element. A second perpendicular 3^c is then erected from the line 1'' at the point corresponding to the outer 90 limit of the face element. The intersection 95 of the perpendicular 3^c with the axis of the arrow 4' gives a point 3^d which is taken as the outer end of the face element. The point 3^d is thus located with respect to line 1'' and is transferred to the same relative 100 location with respect to line 1', as shown at 3^d. There is thus located a point or rather a differential length or section of the outer portion of the element of the club face, by the application of the axiom that the portion of the face in contact with the ball, 105 which corresponds to the arrow 4', shall be at right angles to the line of intended flight. By choosing various points *b* along the line *a*, as indicated at 1, 2, 3, on that line and proceeding as above, the curvature of the outer section of the face element is obtained. Mathematical determination might likewise be made but for convenience and clarity, I have chosen the graphical method.

It will be noted that the curved face above provided will result in presenting to the ball

a striking surface at right angles to the line of intended flight regardless of the angularity of the shaft at the time of percussion, so long as the handle end of the shaft is kept to its proper arc during the swinging of the club, and so long as the handle end of the shaft is brought through ahead of rather than behind the club head. These limitations are met with relative ease as compared with the limitations upon the accuracy of the stroke in prior art clubs.

It should not be understood that it is in practice required that the exact curvature of the striking face as herein worked out graphically need be followed in order to obtain the benefits of the invention. These

benefits will obviously result in great measure from any curvature following the general principles here set forth.

I claim:

1. A golf club of the driver type in which the outer section of the driving face is curved forwardly, that is, in the direction of flight of the ball.
2. A golf club of the driver type in which the outer section of the driving face is curved forwardly, that is, in the direction of flight of the ball, the curvature being progressive so that the remote end of the face has the greatest angularity.

CHARLES H. HAUPT.
